J. S. THOMPSON

BRAKE SHOE

Filed Sept. 16, 1922

FIG. 1

FIG. 2

FIG. 3

FIG. 4

Inventor:

James S. Thompson

By: Wm. J. Clark

Atty.

UNITED STATES PATENT OFFICE.

JAMES S. THOMPSON, OF PELHAM, NEW YORK, ASSIGNEE TO THE AMERICAN BRAKE SHOE & FOUNDRY COMPANY, OF WILMINGTON, DELAWARE, A CORPORATION OF DELAWARE.

BRAKE SHOE.

Application filed September 16, 1922. Serial No. 588,543.

To all whom it may concern:

Be it known that I, JAMES S. THOMPSON, a citizen of the United States, residing at Pelham, in the county of Westchester and State of New York, have invented certain new and useful Improvements in Brake Shoes, of which the following is a specification.

This invention relates to composite shoes of that type which are provided with chilled sections spaced apart on the wearing face throughout its length. It has been found that in shoes of this kind the chilled sections sometimes crack or break away from the body of the shoe in handling and in service owing to the brittle texture of the chilled sections and to the difference between the texture of the chilled sections and the unchilled sections of the body adjacent the chilled sections. This lessens the efficiency of the shoe and if a considerable chunk of the chilled metal is displaced from the body it is apt to result in fracture of the shoe and possible accident.

It is the object of my invention to overcome these objections and to provide a sectionally chilled brake shoe in which the chilled and unchilled sections are bonded together by layers of continuous strips of expanded mild steel or similar tough and ductile material embedded therein, so that the chilled sections are securely anchored in the body and with the other sections of the body and the tendency of the chilled sections to crack and break away is materially reduced and the possibility of chunks of the chilled sections becoming displaced from the shoe is entirely avoided, thereby enabling the shoe to be continued in service without loss of efficiency until worn out.

In the accompanying drawings illustrating selected embodiments of the invention

Fig. 1 is a side elevation of one type of driver shoe embodying my invention and partly shown in section;

Fig. 2 is a face view of the shoe shown in Fig. 1 and also partly in section;

Fig. 3 is a transverse sectional view on the line 3—3 of Fig. 1; and

Fig. 4 illustrates another embodiment of the invention.

I have selected for illustrating the invention a type of driver shoe which is more or less familiar in the art but it will be under-

stood that the invention may be embodied in driver shoes of other kinds and also in any car shoe where it may be useful.

Referring to the drawings, 5 designates the body of the shoe and 6 a plurality of chilled sections at the ends of the shoe and spaced apart therebetween. Shoes of this type are provided with a centrally disposed attaching lug 7 and usually with some form of reinforcing and strengthening back 8. The chilled sections 6 are reinforced in the body of the shoe and bonded to adjacent unchilled sections of the body by a plurality of strips 9 of reticulated metal which are embedded in the shoe and extend approximately from end to end thereof. I prefer to employ expanded metal and to arrange the strips one above the other flatwise to the wearing face of the shoe. Chilled sections may be located at the ends of the shoe and intermediate of these end chills, as shown in Fig. 1, or the end chills may be omitted, as shown in Fig. 4, and any other disposition of the chilled sections may be employed as found desirable to meet different conditions.

The metal strips may be spaced apart slightly, as shown in the drawings, or they may be arranged one upon the other in a more or less compact bundle, if desired, the bundling arrangement having the advantage of facilitating the work of molding the shoe. These metal strips are treated in a suitable manner to preserve the integrity of the metal during the casting operation and they form a strong and substantial reinforcing or bonding medium extending substantially throughout the length of the shoe and securely bonding the chilled and unchilled parts of the shoe together, thereby reinforcing and strengthening the shoe and likewise anchoring each chilled section so that in event of its breaking the danger arising from chunks breaking away from the shoe is avoided and the shoe is enabled to continue in service regardless of cracks or fractures at or about its full efficiency until worn out.

As before stated, the invention may be embodied in other types of shoes than the one illustrated in the drawings and it may be employed with chilled sections differently arranged. I prefer to employ strips made of expanded metal but strips of other reticulated metal may be used if desired.

I claim:

1. A brake shoe comprising a body having a plurality of chilled sections spaced apart on its wearing face, and a reticulated metal strip extending substantially from end to end of said body and embedded therein to bond and anchor the chilled sections in the body.
2. A brake shoe comprising a body having a plurality of chilled sections spaced apart on its wearing face, and a plurality of reticulated metal strips extending substantially from end to end of said body and arranged flatwise to the wearing face of the

shoe and embedded in the body to bond and anchor the chilled sections therein. 15

3. A brake shoe comprising a body having a plurality of chilled sections integral therewith and spaced apart on the wearing face of the shoe, and a plurality of expanded metal strips extending substantially from end to end of said body and arranged one upon the other flatwise to the wearing face of the shoe and embedded therein to bond and anchor all of the chilled sections 20 25 in the body.

JAMES S. THOMPSON.
